INTERLEAF SPACER FOR GROOVED SPRINGS

Nathaniel C. Fick and Nelson A. Crites, Columbus, Ohio, assignors, by mesne assignments, to Standard Steel Spring Company, Coraopolis, Pa., a corporation of Pennsylvania

Application March 27, 1948, Serial No. 17,536

7 Claims. (Cl. 267—50)

1

This invention relates to a new type of interleaf spacer and more particularly to interleaf spacers for use with grooved leaf spring sections.

The need for interleaf spacers in leaf spring assemblies is well established in the art, it being generally recognized that spacers are important in eliminating or markedly decreasing the galling and fretting action which occurs between adjacent spring leaves due to the vibration and torsions to which leaf spring assemblies are constantly subjected. In the past, spacers to fit grooved spring leaves have been formed by sewing, or stapling, two elongated sections of flexible material together so as to produce a ribbed effect in the manner described in U. S. Patent No. 2,148,640 to Pretz, for example. These sewing or stapling processes are rather expensive and have not been widely adopted in practice.

It is, therefore, an object of this invention to provide an interleaf spacer which may be formed easily and economically according to well-known fabrication methods.

It is a further object of this invention to provide an interleaf spacer provided with a suitable reservoir for holding a lubricant material.

Other objects and purposes of this invention will become apparent from a consideration of the appended drawings which illustrate embodiments of the invention wherein:

Figure 1 is a schematic drawing showing the spacer of the present invention;

Figure 2 is a cross-section through a portion of a leaf spring and spacer assembly and illustrates the manner in which a lubricant material may be incorporated in the assembly;

Figure 3 shows a variation of the spacer shown in Figure 1 wherein a perforated reservoir portion is shown; and

Figure 4 is a cross-sectional view of a portion of a leaf-spring-and-spacer assembly, illustrating another form of the spacer of this invention in use with a leaf spring having two grooves.

Referring now more particularly to the drawings, a spacer 10 having a projecting or channel portion 11 extending the length of the element along one side and fashioned to fit securely in the grooved portion of a spring leaf is shown in Figure 1. On the underside of this channel portion 11 is a reservoir-forming portion 12 which may be filled with a lubricating material 14 and which forms an integral part of the projecting portion 11 as is shown in Figure 2. The manner of assembly of the spacers 10 and the spring leaves 15—15 is shown in Figure 2. In Figure 3 it is shown how the spacer 10 may be provided

with perforations 17—17 to permit the passage of a lubricant 14 to the surface of the grooved portion of a spring leaf 15. In Figure 4 a different type of spacer 18 having two projecting portions 19—19 is illustrated in a leaf spring assembly where the spring leaves 20—20 have two grooves. The undersides of the projecting portions 19 and the flat side of the lower leaf 20 form voids which provide reservoirs that may be filled with a lubricating material as is indicated at 21—21. The spacer 18 may, of course, be provided with perforations 22—22 to permit the passage of the lubricant 21 to the surface of the grooved portions of the upper spring leaf 20. It will be readily apparent that spacers suited for use with spring leaves having three, four, five or any given number of grooves could be prepared by providing the spacer with the appropriate number of projections.

Consideration of the assembly illustrated in Figure 2 will reveal that the position of the lubricant reservoir 12 provides for the adequate lubrication of those surfaces which are most likely to be subject to damaging wear and abrasion. Lubrication of those surfaces may be abetted by impregnating the spacer with a suitable lubricant prior to its insertion into the leaf spring assembly. Such impregnation greatly enhances the action of the spacer in reducing friction and fretting between spring leaves.

By means of perforations 17—17, as shown in Figure 3, provision is made for the passage of lubricant 14 from the lubricant reservoir 12 to the compression side of each leaf spring as well as to the tension side of the leaf.

Although many materials have been found to be suitable for use in forming the spacer of the present invention, materials such as rubber, fabric, paper, press-board, or the like, are preferred. Laminates, such as a structure made up of alternate layers of metal and press-board, may also be used for interlining spacers.

An outstanding advantage of the present spacer is that it lends itself to mass-production methods and may thus be produced cheaply and in quantity. As an example of a convenient way of fabricating the spacer, it will be seen that the spacer shape may readily be produced by a rolling and/or pressing or forming operation. The grooved portion 11 may be manufactured by rolling in a process wherein the steps of impregnating the spacer with a lubricant and cutting it into strips of the desired length are included as part of a continuous fabrication operation.

In addition to the purposes and advantages al-

ready pointed out, an important function of the present spacer is to prevent squeaking due to rubbing action between adjacent leaf springs. Other advantages and variations not already mentioned will be obvious to those skilled in the art and should be considered a part of the present invention.

What is claimed is:

1. In a leaf spring assembly comprising a plurality of leaves, each of said leaves having at least one flat side and an oppositely disposed side provided with a groove extending the length of said leaf, an interleaf spacer disposed between adjacent leaves and having a projecting portion extending above the plane of said spacer, extending the length thereof, and formed to fit into said groove, and the underside of said projecting portion extending above the plane of said spacer; said underside of said projecting portion and said flat side of an adjacent leaf forming a void which provides a lubricant reservoir.

2. In a leaf-spring assembly comprising a plurality of leaves, each of said leaves having at least one flat side and an oppositely disposed side provided with grooves extending the length of said leaf, an interleaf spacer disposed between adjacent leaves and having projecting portions extending above the plane of said spacer, extending the length thereof, and formed to fit into said grooves, and the undersides of said projecting portions extending above the plane of said spacer; said undersides of said projecting portions and said flat side of an adjacent leaf forming voids which provide lubricant reservoirs.

3. In a leaf-spring assembly comprising a plurality of leaves, each of said leaves having at least one flat side and an oppositely disposed side provided with grooves extending the length of said leaf, an interleaf spacer disposed between adjacent leaves and having a plurality of projecting portions extending above the plane of said spacer, extending the length thereof, and formed to fit into said grooves, perforations in said projecting portions, and the underside of said projecting portions extending above the plane of said spacer; said undersides of said projecting portions and said flat side of an adjacent leaf forming voids which provide lubricant reservoirs, the perforations permitting the flow of lubricant material to the compression side of the spring leaf.

4. In a leaf-spring assembly comprising a plurality of leaves, each of said leaves having at least one flat side and an oppositely disposed side provided with a groove extending the length of said leaf, an interleaf spacer disposed between adjacent leaves and having a single projecting portion extending above the plane of said spacer, extending the length thereof, and formed to fit into said groove, and the underside of said projecting portion extending above the plane of said spacer; said underside of said projecting portion and said flat side of an adjacent leaf forming a void which provides a lubricant reservoir.

5. In a leaf-spring assembly comprising a plurality of leaves, each of said leaves having at least one flat side and an oppositely disposed side provided with a groove extending the length of said leaf, an interleaf spacer disposed between adjacent leaves and comprising a single integral element and having a projecting portion extending above the plane of said spacer, extending the length thereof, and formed to fit into said groove, and the underside of said projecting portion extending above the plane of said spacer; said underside of said projecting portion and said flat side of an adjacent leaf forming a void which provides a lubricant reservoir.

10 6. In a leaf-spring assembly comprising a plurality of leaves, each of said leaves having at least one flat side and an oppositely disposed side provided with a groove extending the length of said leaf, an interleaf spacer disposed between adjacent leaves and having a projecting portion extending above the plane of said spacer, extending the length thereof, and formed to fit into said groove, and the underside of said projecting portion extending above the plane of said spacer; said underside of said projecting portion and said flat side of an adjacent leaf forming a void which provides a lubricant reservoir; said spacer comprising a single integral element, and with perforations through said projecting portion to said lubricant reservoir.

15 7. In a leaf-spring assembly comprising a plurality of leaves, each of said leaves having at least one flat side and an oppositely disposed side provided with a groove extending the length of said leaf, an interleaf spacer disposed between adjacent leaves and having a projecting portion extending above the plane of said spacer, extending the length thereof, and formed to fit into said groove, and the underside of said projecting portion extending above the plane of said spacer; said underside of said projecting portion and said flat side of an adjacent leaf forming a void which provides a lubricant reservoir; said spacer having as an integral part a perforated lubricant reservoir, whereby lubricant may pass to the compression side of the leaf.
